UNITED STATES PATENT OFFICE.

JOHN W. BOCH, EAST LIVERPOOL, OHIO.

ELECTRICAL INSULATOR AND METHOD OF MAKING SAME.

SPECIFICATION forming part of Letters Patent No. 600,475, dated March 8, 1898.

Application filed October 23, 1897. Serial No. 656,155. (No model.)

To all whom it may concern:

Be it known that I, JOHN W. BOCH, a citizen of the United States of America, residing in East Liverpool, Ohio, have invented Improvements in Electrical Insulators and Methods of Making the Same, of which the following is a specification.

My invention consists of improvements in porcelain or earthenware insulators and in the mode of manufacturing the same.

Insulators constructed in accordance with my invention are more particularly such as are adapted for use on electric lines for the transmission of energy with currents of high voltage.

In the accompanying drawings, Figure 1 is a sectional view illustrating one step in the manufacture of my improved insulator. Fig. 2 is a sectional view of a finished insulator.

20 In the drawings I have shown a triple-petticoat type of insulator, but my invention may be employed in the manufacture of double-petticoat insulators or other styles. The insulator is built up of two or more separately-

25 molded parts of clay. In the case of the triple-petticoat style of insulator it is preferred to make it of three separately-molded pieces of clay. The inner part A is pressed or molded with a threaded or other suitable

30 socket *a* for the reception of the usual pin of iron or other suitable material, and the outer part C, shaped like an inverted bowl, is provided with a cross-notch *c* on the top for the reception of the electrical conductor and has

35 side shoulders *c' c'*, by which the conductor may be wired down. The intermediate part B is made bowl-shaped, and the several parts are molded so as to nest or fit into each other in the manner shown, preferably with corresponding 40 centering projections and recesses *x x*.

In carrying out my invention the separately-molded parts A B C after coming from the press are first dried out separately. This is preferably done in an oven or kiln in the usual manner of drying clay articles by the process known as "biscuit-firing." When 45 these separate parts have thus been biscuit-fired or otherwise dried and are ready to be

50 put into the vitrifying-kiln, they are each coated with a glazing material, preferably all over, as by dipping the article into such liquid glazing material. The two or more parts

of each insulator thus coated are now fitted into each other and are stood upside down, as it were—that is, with the lower ends of the 55 bowls uppermost, as shown in Fig. 1. Glazing material is then put into the joints—that is, into the annular channels between the petticoats—and this may be most conveniently done by pouring the liquid glaze into the 60 channels, as indicated at *y* in said figure. The parts thus put together and supplied with glazing are now put into a saggar with the petticoats uppermost, as shown in Fig. 1, and placed in a kiln, in which under great 65 heat the clay shrinks and becomes vitrified, as usual, and the glazing material melts and becomes of a glass-like character. That glaze which was put into the annular channels between the petticoats flows down into and fills 70 all the spaces between the parts of the insulator, such spaces either being there by lack of correct fit of the parts or arising during the shrinkage by the vitrification of the clay. The result is that the two or more separately- 75 molded parts are firmly united to each other throughout by means of the glass-like glaze.

Owing to the supply of the extra glazing material between the petticoats or at the joints, I prevent the formation of air-spaces 80 or cracks for the entrance of moisture in the finished insulator and which are almost certain to occur in the absence of such provision of additional glazing material. A solid and practically impenetrable layer or layers of 85 glaze will thus be formed between the conductor and the supporting-pin intermediate between the porcelain or earthenware parts of the insulator.

I claim as my invention—

1. The mode herein described of making a petticoat-insulator by molding it in two or more parts of clay, coating them with glazing material, fitting them together, supplying extra glazing material at the joints between the 95 petticoats and firing the united and coated parts with the petticoats uppermost, so that the glazing material will be melted and flow into and fill all the spaces between the parts, substantially as described.

2. The mode herein described of making a petticoat-insulator, by molding it in two or more parts of clay, fitting them together, supplying glazing material at the joints between

the petticoats, and then firing with the petticoats uppermost, whereby the clay will become vitrified, and at the same operation the glazing material will be melted and flow into 5 and fill the spaces between the parts, substantially as described.

3. The mode herein described of making a petticoat-insulator, by molding it in two or more parts of clay, biscuit-firing the parts 10 separately, fitting them together, supplying glazing material at the joints between the petticoats, and firing, with the petticoats uppermost, so that the glazing material will be melted and flow into and fill all the spaces 15 between the parts, substantially as described.

4. As a new article of manufacture, a porcelain or earthenware insulator made of two or more parts fitted one within the other with extra glaze introduced to fill all the spaces where the parts are to be united and forming 20 an intermediate solid layer or layers of glaze between the conductor and pin, substantially as described.

In testimony whereof I have signed my name to this specification in the presence of 25 two subscribing witnesses.

JOHN W. BOCH.
